UNITED STATES PATENT OFFICE.

JAMES F. GOODRIDGE AND ALEXANDER POPE, OF BOSTON, MASSACHUSETTS.

CAR-STARTER.

SPECIFICATION forming part of Letters Patent No. 245,623, dated August 16, 1881.

Application filed February 7, 1881. (No model.)

To all whom it may concern:

Be it known that we, JAMES F. GOODRIDGE and ALEXANDER POPE, both of Boston, in the State of Massachusetts, have invented an Improvement in Car-Starters, of which the following is a specification.

The invention relates to car-starting mechanism making use of a gear-wheel upon the car-axle, in which the teeth of the said gear-wheel are on the side or face thereof, rather than on the periphery, and has especial reference to the varying load of the car. It is particularly applicable to a car-starting mechanism patented to us in Letters Patent No. 234,026, the said former car-starting mechanism consisting, essentially, of a gear-wheel upon the car-axle, and a lever pivoted beneath the car-floor by means of a pin and slot, so as to have both a horizontal swinging and a horizontal sliding motion, and provided with a gear-sector upon its shorter arm, there being suitable guides and springs for throwing the gear-sector and gear-wheel into and out of gear.

As an improvement upon the mechanism patented to us as aforesaid, our present invention consists in the employment of long ratchet-teeth upon the gear-sector and short ratchet-teeth upon the inner face of the gear-wheel, as hereinafter more particularly described, this difference in the length of the teeth permitting the gear-sector to rise and fall with the car-body as the load varies in weight, and to properly engage with the gear-wheel, whatever may be the weight of the load; and so far as our knowledge extends we are the first to provide for the proper and sure engagement with a vertically-faced toothed wheel mounted upon a car-axle of any toothed device controlled by the movements of the draw-bar of the car, notwithstanding variations in the distance between the car-body and car-axle, which are due to variations in the weight of the load.

Another improvement upon our said former invention consists in a latch pivoted to the bearing-plate and yielding to the swinging movement of the starting-lever in one direction, but resisting it in the other, to cause the more certain engagement of the gear-sector and gear-wheel when the car is to be started.

In the drawings, Figure 1 is an inverted plan of mechanism embodying our improvements,

including a part of the car-frame. Fig. 2 is a longitudinal sectional elevation of the same, showing also a section of the car-floor. Fig. 3 is an inverted plan of the bearing-plate enlarged to two and one-half times the size represented in Figs. 1 and 2. Fig. 3^a is a section through line *x x* of Fig. 3. Fig. 4 is a longitudinal section of the starting-lever in the position in which it is shown in Fig. 1, but enlarged and not inverted, together with the corresponding sections of the bearing-plate and car-bottom. Figs. 5, 6, and 7 are details, to be hereinafter explained.

A is a car-frame; B, the floor. C is the car-axle, and D is a car-wheel.

E is the draw-bar having a longitudinal motion in either direction in boxes F F'. A spring, G, coiled around the draw-bar and acting against the box F and collar *a*, tends to throw the draw-bar back. The draw-bar is furnished with a pole-brace, *b*, and a coupling-slot, *c*, in the ordinary manner. It has also a hole, *e*, to receive a pin, *f*, which is on the end of a treadle, *g*, and has a vertical motion therein, as well as through corresponding holes in the box F and car-frame.

H is a gear-wheel, keyed to the car-axle and having short ratchet-teeth *h* upon its inner face, as shown.

I is the bearing-plate secured to the bottom of the car. It has projecting therefrom, and cast in one piece with it, a hub, *i*, a guide, *j*, and a stop, *k*.

J is the starting-lever, fulcrumed upon the hub *i*, and having upon one end a segment-gear provided with deep ratchet-teeth *l*, as shown more clearly in Figs. 5 and 7, while its other end is hinged to a rod, *m*, which connects it with a swinging bar, *K*, in turn connected by a rod, *m'*, with the draw-bar E, as shown. The hub *i* passes through a slot, *n*, in the lever, this method of connection allowing to the lever a sliding as well as a swinging motion.

P is a plate having a round hole fitting upon the hub *i*, where it is held below the lever J by means of a washer, *o*, and a pin, *p*, as shown. The plate P has two ears, *q q*, which are connected by spiral springs *r r* with two hooks, *s s*, inserted in the starting-lever J. This plate has also two flanges, *t t*, which bear

against a strengthening-flange, t' , around the slot n of the starting-lever. Accordingly the plate P partakes of the swinging motion of the lever, but not of the sliding motion, and the 5 springs tend to draw back the starting-lever till the end of the slot n therein, which is near the segment-gear, presses against the hub i . The starting-lever has a pin, p' , working in connection with the guide j and stop k , cast with 10 the bearing-plate, the said guide and stop forming a sweep to control the movement of the starting-lever. The bearing-plate has also pivoted to its upper side, between it and the car-floor, a lever or latch, w , a projection near 15 the free end of which falls through a slot, w' , in the bearing-plate, cut in the path p' between the guide j and stop k , forming the sweep, as before stated. This projection is beveled upon one side, as shown, so that the pin p' may lift 20 the latch and pass freely along the path of the sweep in one direction, but in one direction only, since the other side of the projection upon the latch serves as a stop.

The operation is as follows: The driver puts 25 his foot on the treadle g and thus lifts the pin f from the hole e in the draw-bar F . This allows the team to pull the draw-bar forward a few inches in the boxes F F' , and this motion of the draw-bar is communicated, as is obvious, to the starting-lever J . The projection upon the latch w , resisting the pin p' on the starting-lever, causes that pin to move along the inner side of the guide j' , thereby overcoming the force of the springs $r r$, and the ratcheting 35 teeth t of the gear-sector are consequently made to engage, successively with ratchet-teeth h upon the gear-wheel H , thereby starting the car. The car having been started the pull of the team slackens and the spring G 40 throws back the draw-bar until the pin f falls into the hole e . The backward movement of the draw-bar is positively communicated to the starting-lever, and the latter is forced back to its starting-place, the pin p' being free to 45 travel on the other side of the guide j' , whether it is forced by the springs $r r$, and passing freely under the latch w .

In practice a rubber washer, R , and a reinforcement of the floor, B' , are placed between the bearing-plate I and the true floor B , and 50 both are properly slotted to admit the required movements of the latch w . This construction is shown in Figs. 3^a and 4, but the parts B' and R are omitted in Fig. 2.

It will be observed that the acting faces of 55 the ratchet-teeth lie in radial planes which would meet in the car-axle; but in practice this is immaterial, since very short teeth are here used, as above stated. The acting faces of the long teeth upon the gear-sector are perpendicular. 60

We claim—

1. In a car-starting mechanism embodying a vertically-faced toothed wheel on the car-axle, the combination, with said wheel, of teeth 65 which are made to engage with the gear-wheel by the movements of the draw-bar, and which have long bearing-faces, while the teeth upon said wheel are short, substantially as described, for the purpose specified. 70

2. In a car-starting mechanism consisting, essentially, of a gear-wheel upon the car-axle and a horizontally-swinging gear-sector connected with the motive power, short teeth upon the wheel in combination with long teeth upon 75 the sector, substantially as described, for the purpose specified.

3. In a car-starting mechanism, substantially as described, the latch w in the sweep, in combination with the starting-lever, to insure the initial movement of the starting-lever 80 in the proper direction.

4. In a car-starting mechanism, substantially as described, the latch w , in combination with the starting-lever, and the sweep and 85 springs controlling the lever, for the purpose specified.

JAMES F. GOODRIDGE.
ALEXANDER POPE.
